UNITED STATES PATENT OFFICE.

WOOLF PEIREZ, OF NEW YORK, N. Y., ASSIGNOR, BY MESNE ASSIGNMENTS, TO KATIE SOMMERS, OF BROOKLYN, NEW YORK.

GUTTER HANGER.

Application filed January 27, 1921. Serial No. 440,368.

To all whom it may concern:

Be it known that I, WOOLF PEIREZ, a citizen of the United States, and resident of the city of New York, in the county of 5 Queens and State of New York, have invented certain new and useful Improvements in Gutter Hangers, of which the following is a specification.

The present invention relates to gutter 10 hangers, that is to say to devices for supporting roof gutters.

The main object of the invention is to provide a gutter hanger, including means made integral therewith for anchoring the 15 gutter to the wall of the building.

Another object of the invention is to provide a gutter hanger of the type mentioned which is simple in construction, efficient in 20 operation, durable in use and capable of manufacture on a commercial scale, or in other words one which is not so difficult to make as to be beyond the reasonable cost of such a contrivance.

With these and other objects in view, 25 which will more fully appear as the nature of the invention is better understood, the same consists in the combination, arrangement and construction of parts hereinafter described, pointed out in the appended 30 claims and illustrated in the accompanying drawings, it being understood that many changes may be made in the size and proportion of the several parts and details of construction within the scope of the appended claims, without departing from the 35 spirit or sacrificing any of the advantages of the invention.

One of the many possible embodiments of the invention is illustrated in the accompanying drawings, in which:—

Figure 1 is a side elevation of a gutter hanger constructed in accordance with the present invention; and Fig. 2 is a perspective view of a portion thereof.

In the drawings, the numeral 10 indicates a roof gutter, the outer edge of which is provided with a bead 11, as usual in constructions of this type, while its inner edge 12, adjacent the wall of the building, is 45 plain. For supporting this gutter in proper relation to the roof 13 of the building, there is provided a plurality of hangers, spaced apart a suitable distance, each of said hangers including a gutter embracing strap 14, 50 a transversely extending bar 15 and a

bracket 16, the latter being attached to said bar and roof. The elements of the gutter hanger are made of sheet metal of any preferred gage and united by rivets or other suitable fastening means.

The bar 15 includes an outer hook-shaped section 17, fitting over the bead 11 of the gutter, its opposite end 18 being bent over the plain edge 12 of the gutter, as clearly shown in Fig. 1 of the drawings. To the hook-shaped end 17 of the said bar is fixed, for instance by means of a rivet 19, the gutter embracing strap 14, one end of said strap, denoted by the numeral 20, projecting into the bead 11 for a purpose herein-after to be described, while its other end extends through a slot 21 in the bent portion 18 of the bar 15, and being then bent downwardly into contact with the wall of the building, as shown at 22. The downwardly bent portion 22 of the strap extends below the gutter and is secured to the building wall by a nail 23 or otherwise, to form an anchor for the gutter. In the bent portion 18 of the strap 15 is 70 formed an aperture 24, through which a nail 25 may be driven into the adjacent portion of the wall of the building, in order to secure and hold the gutter in position.

The bracket 16 is joined with the bar 15 by a rivet 26 or otherwise, it including an upwardly extending portion 27 and an outwardly projecting section 28, which is secured by nails 29, or otherwise, to the roof 13, from which the rain water is to be carried off.

In use, the hook-shaped end 17 of the bar 15 is engaged with the bead 11 of the gutter, the end 20 of the gutter embracing strap 14 inserted into the said bead, and the 95 bent portion 18 of the bar 15 engaged with the plain edge 12 of the gutter. After this the strap 14 is bent around the gutter and extended through the slot 21 in the bar 15. The strap is then bent downwards into engagement with the building wall and the nail 23 driven into the wall. The nail 25 is then driven through the bar 15, and, finally, the bracket 16 fastened to the roof.

Inasmuch as the bars and straps wholly 105 surround the gutter and both the ends of the bars and straps are fastened, by the nails 25 and 23, respectively, to the building wall, the gutter is effectively prevented from tilting on the brackets 16. The outer ends 110

20 of the straps 14 are engaged with the bead 11 of the gutter in order to hold the hook-shaped ends 17 of the bars 15 in contact with the bead throughout the lengths 5 of the said hooks.

What I claim is:—

1. A gutter hanger comprising a bar extending transversely of the gutter and provided at its outer end with a hook-shaped 10 section fitting over the bead of the gutter, the opposite end of said bar being fixedly attached to the opposite edge of the gutter, a strap member engageable with the ends of the transversely extending bar and tightly 15 embracing the under surface of the gutter, said strap member having an extension at its outer end adapted for insertion within the beaded edge of the gutter to effectively lock the hook-shaped section in position.

2. A gutter hanger comprising a bar extending transversely of the gutter and provided at its outer end with a hook-shaped section fitting over the bead of the gutter, the opposite end of said bar being fixedly attached to the opposite edge of the gutter, a 25 strap member engageable with the ends of the transversely extending bar and tightly embracing the under surface of the gutter and terminating at its inner end in a depending portion projecting below the gutter, said 30 strap member being provided at its opposite end with an extension adapted for insertion within the beaded edge of the gutter.

Signed at New York, in the county of New York and State of New York, this 25th 35 day of January, A. D. 1921.

WOOLF PEIREZ.
